LESLIE STEVENS, OF GLEN RIDGE, NEW JERSEY, ASSIGNOR TO STEVENS MANUFACTURING CORPORATION, OF NEW YORK, N. Y., A CORPORATION OF DELAWARE

ACOUSTIC DIAPHRAGM

Application filed April 5, 1927. Serial No. 181,028.

This invention relates to acoustic diaphragms and methods of making the same. The object of the invention is to provide an improved large, direct-acting diaphragm, requiring no horn or other sound amplifying device, especially intended for use in radio loud speakers, but also adapted for use as a phonograph reproducer, and as a sound collecting diaphragm for radio transmitting apparatus or phonograph recording apparatus.

A diaphragm according to the invention is a seamless diaphragm made from a continuous piece of one or more layers of plies, usually two, of woven fabric impregnated with stiffening material and stretched and deformed, without folds or laps, to the desired shape while the stiffening material is moist, and held stretched in the shape to which it has been deformed until the stiffening material has become set. The diaphragm is usually made of bulging or dished form, most desirably conical, and better conoidal and continuously curved from its center outward in radial directions rather than of true cone form, and is shaped by being pulled and tensioned against a form which may be heated to secure quick drying and setting of the stiffening material. The interstices of the fabric are filled to make the diaphragm impervious to air, or substantially so, either by using for application to the fabric before it is shaped a stiffening material of a character to serve this purpose, or, and most desirably, by applying to the shaped diaphragm a coating of filling material which also serves to increase the stiffness and resiliency of the diaphragm and to make it water proof. The diaphragm may be made of very light weight and of such degree of flexibility and resiliency as to be highly responsive to sound vibrations. It is very durable and not easily injured as compared to the paper cone-shaped diaphragms commonly used for radio loud speakers and phonograph reproducers, and it is not affected by atmosphere moisture.

In the accompanying drawings,

Figs. 1, 2 and 3 are sectional views of illustrative diaphragms according to the invention.

Fig. 3^a is a sectional view on a larger scale of a part of a diaphragm of the shape of the diaphragm shown in Fig. 3, made of two plies or layers of fabric.

Fig. 4 is a sectional view of a form for shaping diaphragms such as shown in Fig. 1, and a cooperating clamping ring and parts of a press in which the form and clamping ring are mounted.

Figs. 1 and 2 show diaphragms of conoidal form, the main portion of the diaphragm being continuously curved from the center of apex outward in radial directions; the diaphragm shown in Fig. 1 being convexly curved and that shown in Fig. 2 being concavely curved. Fig. 3 shows a diaphragm of true cone shape. When the diaphragm is mounted with its periphery unsupported, that is, when mounted to operate as a free edge diaphragm, it is desirable that it be formed at or adjacent to its peripheral edge with a circumferential corrugation, or reverse bend flange, as shown in Figs. 1 and 2. This corrugation stiffens the edge of the diaphragm and aids in maintaining the diaphragm in shape and increases the definition of sound reproduction when the diaphragm is mounted with its edge free.

The conical diaphragms shown in Figs. 1, 2 and 3 are to be understood as only illustrative of the many forms to which the diaphragms according to the invention may be shaped. They may be made of various other conoidal shapes and other shapes in which the fabric is deformed from the plane of its weave, such deformation of the fabric being accomplished by stretching the fabric, which is then held under tension in the shape to which it has been stretched until the sizing or stiffening material with which the fabric is impregnated has become set.

The shaping apparatus illustrated in Fig. 4 comprises a metal form 10 shown as shaped to form a diaphragm such as shown by Fig. 1, in which, as in the diaphragms shown in Figs. 2 and 3, the central portion *a* of the material is displaced from the plane of its peripheral portion *b* and intermediate portions *c* extend at an angle to said plane. The form 10 is mounted on the bed plate 11 of any suitable

press having an upper member 12, and means for causing an approaching movement between the bed plate 11 and such upper member, usually by downward movement of the upper member. The upper member or cross head 12 of the press carries depending therefrom a clamping ring 13 which is formed to cooperate with the peripheral portion of the form 10. The form 10 and the clamping ring 13 are shaped to form a circumferential corrugation such as shown in Fig. 1, near the edge of the diaphragm, the form for this purpose being provided with a circumferential bead 14 and the clamping ring with a corresponding circumferential channel or recess 15. The form and the clamping ring are most desirably heated, as by means of a ring burner 16 for heating the form and a ring burner 17 for heating the clamping ring.

20 In making a diaphragm in accordance with the invention, using shaping apparatus such as shown in Fig. 4 for shaping the diaphragm, the procedure is as follows.

The fabric to be used is most desirably flat woven plain cross-weave fabric of cotton or other suitable material, although other woven fabric might be used. The term "woven fabric" is intended to include fabric known as knitted or crocheted fabric, although a 25 knitted or crocheted fabric is not ordinarily so desirable as a plain cross-weave fabric. The piece of fabric to be used in making the diaphragm may be a single sheet or layer or may be of several sheets or layers laid together, the number of layers, one or more, depending on the weight of the fabric used, and the desired weight or thickness of the diaphragm. I have usually found it most desirable to make the diaphragms of two plies or 30 layers of rather thin open-mesh cotton fabric, one layer being of fine net and the other of a somewhat closer woven cloth such as or resembling cheese cloth. Such a two-ply diaphragm is illustrated by Fig. 3. The piece of 35 fabric, whether of one or more layers, is a continuous piece, that is, without any cut or slit therein. The fabric before being shaped has applied thereto suitable sizing or stiffening material, such as a solution of starch or 40 water-soluble glue. Usually the fabric is sized, or treated with the stiffening material, and allowed to dry. Then, before shaping, the piece of fabric is dampened sufficiently to 45 soften but not to wash out the stiffening material. The piece of fabric is then placed on the shaping form 10, which is heated to a 50 suitable temperature, most desirably about 200° F., and the material is then pulled out smoothly over the form, all wrinkles being 55 pulled out, and while it is held stretched over the form the press is operated to lower the clamping ring to clamp the edge of the material against the peripheral portion of the 60 form and to shape the circumferential corrugation. The diaphragm is then left 65

clamped on the form until the moisture has dried out and the stiffening material is set. It is then removed from the form. When removed from the form the diaphragm is stiff enough to retain its shape, the stiffened fabric 70 being flexible and resilient.

The stiffening material which I find it most desirable to use for applying to the fabric before shaping the diaphragm does not make the diaphragm as stiff as it desirably should be, the interstices of the fabric are not filled and the diaphragm is more or less pervious to air and not suitable for use as an acoustic diaphragm, and it will not stand exposure to moist atmosphere. The diaphragm is therefore additionally treated to further stiffen it, to fill the interstices of the fabric, and to render it waterproof. This is accomplished most desirably by the application to both sides of the diaphragm of a 75 coating of filling and stiffening and waterproofing material consisting of a quick-drying liquid binding agent containing a metallic powder. The binding agent which I have found most suitable is a nitro-cellulose 80 lacquer consisting of nitro-cellulose dissolved in amyl acetate with a small percentage of gum or wax to keep it from becoming brittle when dried, and a suitable mixture is formed by adding about one half ounce of 85 aluminum powder or one ounce of bronze powder to two ounces of the solution. This mixture may be brushed or sprayed on to the diaphragm and this should be done as soon as possible, or before the shaped diaphragm has been exposed for any considerable length of time to a moist atmosphere. The powder in the mixture held by the 90 binding agent serves as a filler for the interstices in the fabric, and the binding agent adds stiffness to the diaphragm and proofs it against moisture. By applying a sufficiently heavy coating of the lacquer or other stiffening and water-proofing material to the diaphragm, the interstices in the fabric may 95 be filled without the use of insoluble powdered material added to the lacquer, but this is not usually desirable for the reason that the heavy coating required adds substantially to the weight of the diaphragm. Powdered material other than metallic powder 100 might be used, but the metallic powder seems to have the advantage of increasing the resiliency of the diaphragm. The use of powdered aluminum is especially desirable because of its comparatively light weight and also apparently because of other characteristics of this metal.

The filling and further stiffening material should be applied to the diaphragm before the sizing, or stiffening material, which is applied to the fabric before it is shaped has been allowed to become softened through exposure to moist atmosphere, and the latter applied material should be of such char- 105 110 115 120 125 130

acter that it will not itself act to soften the sizing. As stated, the sizing, or first applied stiffening material, is most desirably a water-soluble material, and in order to avoid the softening of this material by the later applied filling and stiffening material, this latter material should be made with a solvent which does not readily dissolve the sizing, or should be a quick-drying liquid, and may desirably have both of these characteristics.

An open mesh, rather than a close or tight-woven fabric, is used because of its being more adaptable to being deformed from the plane of its weave, having its warp and woof strands displaced from their normal relation, and also because of its being more freely pervious to air with the sizing applied thereto than a close-woven fabric. When the fabric is being stretched over the form, pocketing of air between the form and the fabric would prevent the fabric from coming accurately to shape against the whole surface of the form. As it is most desirable to use a form having a smooth impervious surface, such pocketing of air is best avoided by having the fabric freely pervious when being shaped on the form. Therefore, not only should a comparatively open mesh fabric be used, but the sizing or filling material applied to the unshaped fabric should be such as not to make the fabric impervious to air, a filling material being applied after the fabric has been shaped to fill the interstices of the fabric and make the diaphragm impervious to air or substantially so.

The diaphragms may be made of practically any size to act directly with the surrounding air without requiring the use of a horn or other sound amplifying means when the diaphragm is used for sound reproduction or as a sound concentrating means when the diaphragm is used for sound recording, and the shape to which the diaphragms are formed may vary widely from those shown. The diaphragms have usually been made round, and from 9 inches to 21 inches in diameter, but they may be made larger than 21 inches in diameter or somewhat smaller than 9 inches in diameter. The size of the diaphragm, as is well known, has an effect on the quality of sound reproduction. Diaphragms of conical shape have been found the best so far for sound reproduction, either in radio loud speakers or in phonograph recorders, and while a conical diaphragm of true cone shape, as shown in Fig. 3, may readily be made by my method, a conoidal shape in which the diaphragm is continuously curved in radial directions, as shown in Figs. 1 and 2 for example, is found to give better sound reproduction than one of true cone shape, and the invention is of especial value because of its adaptability to the production of seamless diaphragms of this form.

In the stretching and deforming of the fabric in shaping the diaphragm, the fabric is pulled into the desired shape without any folding, or lapping, of any parts thereof which are to form part of the diaphragm, and it is put under tension in all directions and is held under such tension until the sizing or stiffening material with which the fabric is impregnated has become set. The result is that the fabric, woven from strands of cotton or other material having some degree of elasticity, is held under tension by the stiffening material, which in turn must be under some degree of compression caused by the tension of the strands of the fabric. This, together with the characteristic elasticity of the stiffening material, causes the diaphragm to have a high degree of elasticity or resiliency. In addition to this characteristic of being highly resilient, the diaphragm, as stated, may be made of very light weight and of any desired degree of flexibility, and as a result of these characteristics diaphragms according to my invention are very efficient for sound reproduction, both in the matter of loudness and quality of reproduction.

What is claimed is:—

1. The method of making large, direct-acting, acoustic diaphragms of conical form, which comprises stretching a continuous piece of flat-woven fabric impregnated with stiffening material in a moist condition over a form to shape the fabric without lapping and to tension it in all directions, holding the fabric stretched on the form until the stiffening material has become set, and thereafter applying to the diaphragm material to fill the interstices in the fabric and to waterproof and further stiffen the fabric.

2. The method of making large, direct-acting, acoustic diaphragms, which comprises stretching a continuous piece of woven fabric impregnated with a water-soluble stiffening material in a moist condition over a form to shape and tension the fabric without lapping, holding the fabric stretched on the form until the stiffening material has become set, and applying to both sides of the diaphragm a coating of quick drying, filling and water-proofing material to fill the interstices of the fabric and to make the diaphragm resistant to atmospheric moisture.

3. The method of making large, direct-acting, acoustic diaphragms, which comprises stretching a continuous piece of woven fabric impregnated with stiffening material in a moist condition over a form to shape and tension the fabric without lapping, holding the fabric stretched on the form until the stiffening material has become set, and applying to the diaphragm a coating of material comprising a binding solution and a metallic powder.

4. The method of making large, direct-

- acting, acoustic diaphragms of conical form, which comprises stretching a continuous piece of woven fabric impregnated with stiffening material in a moist condition to deform the fabric from the plane of its weave to the desired shape of the diaphragm, and holding the fabric stretched in the shape to which it has been deformed until the stiffening material has become set.
5. The method of making large, direct-acting, acoustic diaphragms, which comprises stretching a continuous piece of flat-woven fabric impregnated with stiffening material in a moist condition and deforming it from the plane of its weave to the desired shape of the diaphragm, holding the fabric stretched in the shape to which it has been deformed until the stiffening material has become set, and thereafter applying material 15 to the diaphragm to fill the interstices in the fabric and to further stiffen the fabric.
6. A seamless and lapless large, direct-acting, acoustic diaphragm consisting of a continuous piece of stretched fabric deformed out of the plane of weave, the fabric being impregnated with stiffening material which imparts stiffness and resiliency to the fabric.
7. A seamless and lapless large, direct-acting, acoustic diaphragm consisting of a continuous piece of stretched woven fabric deformed out of the plane of weave, the fabric being under tension and being impregnated with elastic stiffening material.
- 30 8. A seamless and lapless, large, direct-acting, acoustic diaphragm, consisting of a continuous piece of stretched woven fabric having its central portion displaced from the plane of its peripheral portion and with intermediate portions extending at an angle to said plane, the fabric being under tension and being impregnated with stiffening material which stiffens the fabric and renders it resiliency.
- 40 9. A seamless and lapless, large, direct-acting, acoustic diaphragm, consisting of a continuous piece of stretched woven fabric having its central portion displaced from the plane of its peripheral portion and with intermediate portions extending at an angle to said plane, the fabric being under tension and being impregnated with a stiffening material which stiffens the fabric and renders it resiliency, and having applied thereto a coating of filling and stiffening material which fills the interstices of the fabric and further stiffens it.
- 50 10. A seamless and lapless large, direct-acting, acoustic diaphragm, consisting of a continuous piece of stretched woven fabric having its central portion displaced from the plane of its peripheral portion and with intermediate portions extending at an angle to said plane, the fabric being treated with stiffening and filling material which stiffens the fabric and renders it resiliency and fills the interstices thereof.
5. A seamless large, direct-acting, acoustic diaphragm, consisting of a continuous piece of stretched woven fabric having its central portion displaced from the plane of its peripheral portion and with intermediate portions extending at an angle to said plane, the fabric being impregnated with a stiffening material which stiffens the fabric and renders it resiliency, and having applied thereto a coating of filling material comprising a binding agent and a metallic powder.
11. A seamless large, direct-acting, acoustic diaphragm, consisting of a continuous piece of stretched woven fabric having its central portion displaced from the plane of its peripheral portion and with intermediate portions extending at an angle to said plane, the fabric being impregnated with a stiffening material which stiffens the fabric and renders it resiliency, and having applied thereto a coating of filling material comprising a binding agent and a metallic powder.
12. A seamless large, direct-acting, acoustic diaphragm, consisting of a continuous piece of stretched woven fabric having its central portion displaced from the plane of its peripheral portion and with intermediate portions extending at an angle to said plane, the fabric being impregnated with a stiffening material which stiffens the fabric and renders it resiliency, and having metallic aluminum applied thereto in quantity sufficient to fill the interstices of the fabric and held by a binding agent.
13. A seamless, large direct-acting, conical acoustic diaphragm, consisting of a continuous piece of stretched woven fabric, the fabric being stiffened and held in shape and rendered resiliency by an impregnating stiffening material.
14. A seamless large, direct-acting, conical acoustic diaphragm, consisting of a continuous piece of stretched woven fabric, the fabric having applied thereto an elastic stiffening and filling and water-proofing material some of which impregnates the fabric.
15. A large, direct-acting, conical acoustic diaphragm, consisting of a continuous two layer piece of stretched woven fabric, the fabric being stiffened and held in shape and the layers of the fabric being cemented together by impregnating stiffening material.
16. A large, direct-acting, acoustic diaphragm, consisting of a continuous piece of stretched flat-woven fabric comprising a plurality of layers of different mesh deformed out of the plane of weave, the fabric being stiffened and held in shape and the layers of the fabric being cemented together by impregnating stiffening material.
17. A large, direct-acting, acoustic diaphragm, consisting of stretched woven fabric held in shape by stiffening material and having a filling of powdered metal.
- In testimony whereof I have hereunto set my hand.
- LESLIE STEVENS.
